UNITED STATES PATENT OFFICE.

CECIL F. OUTLAW, OF RICHMOND, VIRGINIA.

MAGAZINE-GUN.

SPECIFICATION forming part of Letters Patent No. 738,568, dated September 8, 1903.

Application filed October 18, 1902. Serial No. 127,857. (No model.)

To all whom it may concern:

Be it known that I, CECIL F. OUTLAW, a citizen of the United States, residing at Richmond, in the county of Henrico, State of Virginia, have invented certain new and useful improvements in Magazine-Guns; and I do hereby declare the following to be a full, clear, and exact description of the invention, such as will enable others skilled in the art to which it appertains to make and use the same.

This invention relates to magazine-guns of the rapid-fire type; and it has for its object to provide a construction wherein the cartridges may be fed into a hopper from which they will pass to a carrier which will present them successively in the path of a hammer for discharging them, the cartridges after being discharged being automatically ejected from the carrier.

Other objects and advantages of the invention will be understood from the following description.

In the drawings forming a portion of this specification, and in which like numerals of reference indicate similar parts in the several views, Figure 1 is a side elevation of a gun embodying the present invention. Fig. 2 is a vertical section taken longitudinally through the barrel of the gun, the carrier, the hopper, and the magazine. Fig. 3 is a longitudinal section taken horizontally through the barrel and including the carrier, the firing-pin being in elevation. Fig. 4 is a top plan view of the ejecting-plate.

Referring now to the drawings, there is shown a gun comprising a barrel 5, having the usual longitudinal bore 6, and through one side of the barrel and intersecting the bore is an arc-shaped slot 7, which is adapted to receive the carrier for the cartridges. The carrier in question consists of a wheel including a hub portion 8, which is mounted upon a stub-shaft 9, which projects laterally from the rear end portion of the barrel and from which hub radiate the spokes 11, which carry the rim 12 of the wheel, said rim projecting laterally beyond the spokes at one side and entering the arc-shaped slot 7, in which said projecting portion of the rim is movable and in which it fits.

In the rim 12 of the carrier and radially thereof are formed perforations 13, which re-

ceive the cartridges and carry them successively through the slot 7 and into alinement with the bore 6.

To feed the cartridges to the perforations 13, a hopper 14 is provided, from which leads the magazine 15 in the form of a tube, the lower end of the magazine terminating close to the inner periphery of the rim 12, so that the cartridges will drop from the magazine successively into the perforations 13. The magazine 15 stands vertically, so that the cartridges may be readily dropped into place, and to keep the cartridges from dropping from the perforations as the carrier is rotated a retaining device or keeper 16 is provided. The keeper 16 is in the form of a metal plate attached to the gun-barrel by means of suitable braces 17, and this metal plate is of arc shape and lies close to but spaced from the inner periphery of the rim 12, said plate extending from the magazine, where its end is turned up to the upper face of the barrel adjacent to the slot 7. Directly after receiving the cartridges the perforations, with their cartridges, pass beneath the keeper 16, and should a cartridge tend to drop from a perforation its outer end will rest against the keeper and its outward movement will be stopped, said keeper having a groove 18 in its face to prevent engagement of the keeper with the caps in the ends of the cartridges, so that danger of exploding the cartridges is eliminated.

To explode the cartridges successively as they are brought into alinement with the bore of the barrel, a firing-pin 19 is provided, which is disposed for longitudinal movement in the breech of the gun and is held normally and yieldably projected by means of the helical spring 20, the engaging end of a firing-pin lying normally slightly retracted from position to engage the caps of the cartridges. When the firing-pin is forced backwardly and then released, the cap of the cartridge is engaged and exploded. To force the firing-pin backwardly and then release it, said pin has an arm 21, which extends at right angles thereto and the outer end of which is in the path of movement of an annular series of cams 22, formed on the inner face of the rim 12, there being one cam for each of the perforations 13, so that as the carrier is rotated the arm will be engaged and pressed

rearwardly and then released by the cams successively.

To eject the cartridge-shells, a pivoted plate 23 is employed and is supported at the lower end of an arm 24 on the barrel 5. The forward end of the plate 23 is forked and is disposed in the groove 25 in the inner face of the rim 12, so that the sides of the fork may engage beneath the flanges of the cartridges, after which the plate 23 may be tilted to withdraw the shells. To move the plate 23 into position to engage the flanges of the cartridge-shells, the rear end of the plate has a laterally-directed lug 25' in the path of movement of the cams 22, and when a cam strikes the lug 25' the rear end of the plate is raised, while the forward end thereof is lowered to engage the shell. When the cam moves from beneath the lug 25', the rear end of the plate 23 is depressed by means of the helical spring 26, which is disposed between the rear end of the plate and the lug 27 on the arm 24, this action of the spring serving to tilt the plate and raise the shell engaged thereby.

With the present construction it will be seen that when the carrier is rotated the cartridges which have been placed in the magazine will feed successively into the perforations of the carrier and will be presented successively to the rear end of the bore of the gun. When each cartridge reaches the bore of the gun, the firing-pin will be operated to explode its cap, and after each cartridge has been fired the empty shell will be engaged by the ejector and be thrown from the carrier. These several steps in the operation of the gun are automatic and require only that the carrier be rotated.

In practice it will be understood that modifications of the specific construction shown may be made and that any suitable materials and proportions may be used for the various parts without departing from the spirit of the invention.

What is claimed is—

1. A gun comprising a barrel having a lateral slot intersecting its bore, an annular carrier engaged in the slot and movable therethrough, said carrier being adapted to receive and present cartridges successively to the bore of the gun, and means operated by movement of the carrier for exploding the cartridges.

2. A gun comprising a barrel having a slot extending vertically therethrough and opening in one side of the barrel and intersecting the bore of the barrel, a carrier pivoted to the barrel and including an annular rim engaged with the slot and movable therethrough, said rim having radial perforations to receive cartridges and present them to the bore, a spring-pressed firing-pin for engagement with the cartridges successively and having an arm projecting therefrom, and a series of cams carried by the rim and disposed to successively engage the arm and force the pin rearwardly, and subsequently release it.

3. A gun comprising a barrel, an annular carrier pivoted to the barrel, said barrel having a transverse slot intersecting the bore and through which the carrier is disposed to move, said carrier having radial perforations to receive cartridges, a magazine disposed radially of the carrier for registration with the perforations successively to discharge cartridges thereto, an arc-shaped keeper-plate disposed adjacent to the inner face of the carrier and extending from the magazine to the barrel at the point of entrance of the carrier, a firing-pin, an ejector for the carrier and a common means upon the carrier for actuating the firing-pin and the ejector.

4. A gun comprising a barrel having a transverse slot intersecting its bore, an annular carrier pivoted to the barrel and movable through the slot, said carrier having radial perforations to receive cartridges, means for feeding the cartridges to the perforations, means for exploding the cartridges successively including cams carried by the carrier, and an ejector for the cartridge-shells comprising a pivoted plate having a forked end disposed for engagement beneath the flanges of the shells and having its opposite end in the path of movement of the cams for successive engagement thereby to move the plate and engage it with the shells successively, and a spring disposed to return the plate when released by the teeth.

In testimony whereof I affix my signature in presence of two witnesses.

CECIL F. OUTLAW.
